(57) **CLAIM**

The ornamental design for a tray for a vial and vial adapter, as shown and described.

DESCRIPTION

FIG. 1 is a top, right, rear perspective view of a tray for a vial and vial adapter showing our new design;

FIG. 2 is a top plan view thereof;

FIG. 3 is a bottom, left, rear perspective view thereof;

FIG. 4 is a bottom plan view thereof;

FIG. 5 is a right side elevation view thereof, the left side view being a mirror image thereof;

FIG. 6 is a front elevation view thereof;

FIG. 7 is a rear elevation view thereof;

FIG. 8 is a top, right, rear perspective view thereof, wherein the tray for a vial and vial adapter contains an exemplary vial and vial adapter in an unassembled configuration; and, FIG. 9 is a top, right, rear perspective view thereof, wherein the tray for a vial and vial adapter contains an exemplary vial and vial adapter in an assembled configuration.

The broken line showing in FIGS. 8 and 9 is for the purpose of illustrating environmental structure and forms no part of the claimed design.

1 Claim, 9 Drawing Sheets
